UNITED STATES PATENT OFFICE.

JOHN M. ROWE, OF CLAIBORNE, OHIO, ASSIGNOR OF ONE-HALF TO
JEREMIAH ELLINGWOOD.

FENCE.

SPECIFICATION forming part of Letters Patent No. 249,797, dated November 22, 1881.

Application filed September 10, 1881. (No model.)

To all whom it may concern:

Be it known that I, JOHN M. ROWE, of Clai-
borne, in the county of Union and State of
Ohio, have invented certain new and useful

5 Improvements in Fences; and I do hereby de-
clare that the following is a full, clear, and
exact description of the invention, which will
enable others skilled in the art to which it
appertains to make and use the same, refer-
10 ence being had to the accompanying drawings,
which form a part of this specification.

Figure 1 is a side view of a section of my
improved fence. Fig. 2 is a vertical transverse
section taken through one of the posts or braces.
15 Fig. 3 is a top view. Fig. 4 is a view of one
of the posts or braces detached; and Fig. 5 is
a detail view of one of the panels.

Corresponding parts in the several figures
are denoted by like letters of reference.
20 This invention relates to portable fences;
and it consists in certain improvements in the
construction of the same, which will be here-
inafter fully described, and particularly pointed
out in the claim.

25 Referring to the drawings hereto annexed,
A represents one of my improved fence posts
or supports, which consists of a pair of parallel
uprights, B B, secured between a pair of hori-
zontal foot-rails or base-pieces, C C, and hav-
30 ing their upper ends connected by braces or
binders D D. The ends of the base-pieces pro-
ject beyond the uprights, as shown at E, thus
forming slots F, through which the stakes G,
which secure the posts, may be driven into the
35 ground.

The fence-panels H are constructed of hori-
zontal parallel rails or braces I, which are con-
nected by a central vertical brace, J, and by
vertical braces K at the ends of and on opposite
40 sides of the panel.

Adjustable in the posts or uprights between
the parts B, C, and D are a pair of vertical
rods or bars, L, between which the adjoining
ends of the panels are adjusted, with the end

45 braces, K, engaging each other, after which
wedges M are driven between the uprights B
and rods L, thus binding the panels in posi-
tion and securing the fence.

When it is desired to construct a curved or cir-
cular fence—as, for instance, around a stack—
50 the bars L may be placed between the fence-
panels and the wedges M driven between the
ends of the latter and the uprights B.

Common rails may also be employed in the
construction of my improved fence by adjust-
55 ing or building the rails between the bars L
and afterward tightening the latter by the
wedges M, as above described.

When the panels are used a sliding gate
may be formed at any place in the fence by
60 temporarily withdrawing the wedges holding
one of the panels, which may then be readily
and conveniently slid aside.

From the foregoing description, taken in
connection with the drawings hereto annexed, 65
the operation and advantages of my invention
will be readily understood.

The fence is simple in construction, inexpen-
sive, and may be easily and quickly put up or
taken down.

Having thus described my invention, I claim
and desire to secure by Letters Patent of the
United States—

As an improvement in fences, the combina-
tion of the post A, consisting of uprights B, 75
base-pieces C, and braces D, the adjustable
and removable bars L, the panels H, having
braces K, and the wedges M, substantially as
herein described, for the purpose shown and
specified.

In testimony that I claim the foregoing as
my own I have hereto affixed my signature in
presence of two witnesses.

JOHN M. ROWE.

Witnesses:

ENOS BATY,
HYLAS S. MOORE.
